UNITED STATES PATENT OFFICE.

WALTER M. McLEAN, OF PITTSBURG, PENNSYLVANIA.

DESIGN FOR A SHOW-CASE.

No. 37,934.

Specification for Design.

Patented April 3, 1906.

Application filed February 8, 1906. Serial No. 300,190. Term of patent 14 years.

To all whom it may concern:

Be it known that I, WALTER M. McLEAN, a citizen of the United States, residing at Pittsburgh, in the county of Allegheny and State of Pennsylvania, have invented a new, original, and ornamental Design for Show-Cases, of which the following is a specification, reference being had to the accompanying drawing, forming part thereof.

The figure is a perspective view of a show-case showing my new design.

I claim—

The ornamental design for a show-case, as shown.

WALTER M. McLEAN.

Witnesses:

ROBERT C. TOTTEN,
G. C. RAYMOND.
